United States Patent

Des. 238,292
Patented Dec. 30, 1975

238,292

NECKLACE

Alfred Joseph Durante, 111—46 76th Drive,
Forest Hills, N.Y. 11375

Filed Apr. 24, 1974, Ser. No. 463,752

Term of patent 14 years

Int. Cl. D11—01

U.S. Cl. D45—16 R

FIG. 1 is a front elevational view of a necklace showing my new design; and

FIG. 2 is a side elevational view.

The rear and other side views are mirror images of the necklace shown in FIGS. 1 and 2, respectively.

I claim:

The ornamental design for a necklace, as shown and described.
